E. HAKEY

PIPE WRENCH

Filed Sept. 16, 1922

Inventor
E. Hakey.

Atchison, Topeka & Santa Fe
By *Alfred J. Dooley*
Attorney

UNITED STATES PATENT OFFICE.

ELI HAKEY, OF SWANTON, VERMONT.

PIPE WRENCH.

Application filed September 16, 1922. Serial No. 588,633.

To all whom it may concern:

Be it known that I, ELI HAKEY, a citizen of the United States, residing at Swanton, in the county of Franklin and State of Vermont, have invented certain new and useful Improvements in Pipe Wrenches; and I do hereby declare the following to be a full, clear, and exact description of the invention, such as will enable others skilled in the art to 10 which it appertains to make and use the same.

The invention has relation to tools and more particularly to a wrench for turning pipes, rods and the like required to be 15 coupled by means of a screw-thread joint.

The invention provides a tool of the character aforesaid which is readily adapted to be adjusted to the work and which in operation will readily ratchet so that the work 20 may be effectually gripped as the wrench is oscillated.

Other objects and advantages will be apparent and suggest themselves as the nature of the invention is understood.

25 While the drawings illustrate an embodiment of the invention it is to be understood that in adapting the same to meet different conditions and requirements, various changes in the form, proportion, and minor details of 30 construction may be resorted to without departing from the nature of the invention.

Referring to the accompanying drawings forming a part of the application,

Figure 1 is a side view of a pipe wrench 35 embodying the invention,

Fig. 2 is a detail view showing the relation of the parts when the adjustable jaw is released, and

40 Figs. 3 and 4 are sectional views on the lines 3-3 and 4-4 of Fig. 2, the one looking to the left and the other to the right as designated by the arrows.

45 Corresponding and like parts are referred to in the following description and designated in the several views of the drawings by like reference characters.

The wrench comprises a handle 1 which is provided at its outer end with a fixed jaw 2. An adjustable and pivoted jaw 3 is 50 mounted upon the handle 1 and embodies a shank 4 having its rear end curved as indicated at 5. A shackle 6 pivoted to the

jaw 2 at 7 embraces opposite sides of the shank 4 and the outer edge thereof and admits of a limited pivotal movement of the 55 jaw 3. A loop 8 fast to the rear end of the shank 4 depends therefrom and receives the handle 1 which is slidable therethrough. A dog 9 is pivoted to the loop 8 at 10 and cooperates with teeth 11 along the lower 60 edge of the handle 1 whereby to hold the jaw 3 in the required adjusted position. The dog 9 has a rear depending portion 12 to be engaged by a digit of the hand when it is required to disengage the dog from the teeth 65 11 to admit of adjustment of the jaw 3. A finger piece 13 projects laterally from the rear portion of the dog 9 for a like purpose to the depending part 12. A spring 14 fast at one end to the loop 8 coacts with the 70 dog 9 to hold it in engagement with the teeth, whereby to maintain the jaw 3 in the required adjusted position.

In the operation of the wrench, after the 75 jaw 3 has been adjusted to the work, the handle 1 in effect pivots on the end of the dog 9 and the latter oscillates on its pivot 10, the shackle 6 playing up and down as the handle is oscillated in the ratchet action of the wrench in a manner well understood. 80

What is claimed is:

A wrench of the character specified comprising a handle provided at its outer end with a fixed jaw, an adjustable jaw having a shank resting on the upper edge of the handle, a shackle pivoted to the outer end of the handle and loosely engaging said shank, the rear end of said shank being upwardly curved, a loop secured to the rear end of the shank about said curved portion and depending from the shank and loosely receiving the handle, the lower edge of said handle being provided with teeth, a pivoted dog carried by said loop and selectively engageable with said teeth, and a spring carried by the lower portion of said loop and acting to normally hold said dog in engagement with a selected one of said teeth. 95

In testimony whereof I affix my signature in presence of two witnesses.

ELI HAKEY.

Witnesses:

HOWARD A. ROY,
LEIGH O. PAQUETTE.
